MACHINE FOR OPERATING ON SHOES

Corwin W. Baker, Stoneham, Mass., assignor to
United Shoe Machinery Corporation, Flemington, N. J., a corporation of New Jersey

Application April 23, 1946, Serial No. 664,297

9 Claims. (Cl. 12—67.2)

1

This invention relates to machines for operating upon shoes and is herein illustrated as embodied in a machine of the type disclosed in United States Patent No. 2,323,942, granted July 13, 1943, upon an application filed in the name of Homer F. Smith, which discloses mechanism particularly adapted for pounding the inseam materials and for flattening the welts of lasted shoes.

Heretofore, in the manufacture of welt shoes, after the welt has been attached to the upper and insole, of a lasted shoe and the inseam materials trimmed, it has been customary to pound down the inseam materials and to pound down or stretch out the welt to form a substantially flat shoe bottom to which the outer sole can be attached. This operation is usually performed by means of rolls or hammers which operate upon the inseam materials to reduce them to a common level and to beat or otherwise flatten the welt to conform it to the plane of the shoe bottom. During this operation it is common practice to slash the welt around the sharply curved toe portion of the shoe so that the welt can be made to lie flat. An object of the present invention is to provide in a machine of the type referred to improved welt slashing mechanism which is readily adaptable to operation upon welts of varying thicknesses to produce substantially uniform results.

To this end, and as illustrated, there is provided a work support having a rotatable roll adapted to enter the welt crease of a shoe being operated upon, a feed wheel adjacent to the roll for engaging the welt of the shoe to advance the shoe past the roll, and a plurality of rotatable hammers arranged to engage the inseam materials, as the shoe is advanced, to beat them down to a predetermined level, together with welt slashing mechanism mounted upon the work support and arranged for movement therewith relatively to the feed wheel, the slashing mechanism normally being inoperative but arranged for operation under manual control. By mounting the slashing mechanism for movement with the work support, the slashing knife can be brought into the same position relatively to the work support regardless of the position of the support heightwise of the feed wheel. In view of this, the slashes are made to a predetermined distance from the grain side of the welt which is normally positioned upon the work support. This avoids any likelihood of piercing the grain side or distorting it in such manner as to mar the appearance of the finished shoe.

2

These and other features of the invention are disclosed in the following specification and in the accompanying drawings and are pointed out in the claims.

- 5 In the drawings,
Fig. 1 is a perspective view of a seam beating and welt flattening machine constructed in accordance with one embodiment of my invention;
Fig. 2 is a view in side elevation of the machine
10 shown in Fig. 1;
Fig. 3 is a side view, partly in section, illustrating a shoe in operative position in the machine;
Fig. 4 is a plan view of a portion of a shoe after it has been operated upon by the machine;
15 Fig. 5 is a front view of the upper portion of the machine illustrating the knife actuating mechanism with the parts in an operative position;
Fig. 6 is a front view of a portion of the machine illustrating details of the knife actuating mechanism with the knife in operative position, and
20 Fig. 7 is a view in side elevation, partly in section, illustrating details of the work support and associated mechanism.
- The machine is especially adapted to operate
25 upon lasted shoes, such as a shoe 10 (Fig. 3) having a ribbed insole 12 and a welt 14 stitched to the insole rib through materials of an upper 16, the welt, upper materials and rib having been trimmed along the inseam to produce a surface 18.
30 The machine is for the purpose of beating down the inseam materials to reduce their height to a common level and to stretch out the welt 14 so that it lies substantially in the plane of the reduced inseam.
- 35 The mechanism for accomplishing this comprises a work support 20 (Figs. 1 and 3), carried by the frame 22 of the machine, a feed wheel 24 mounted for rotation about a fixed axis adjacent to the support for engaging the welt 14 of the
40 shoe to advance it across the upper surface of the support, beating hammers 26 rotatably mounted adjacent to the work support for engaging the inseam materials to beat them, and a slashing knife 28 mounted for movement along the work
45 support in the direction of feed for slashing the welt around the toe as shown at 30 (Fig. 4), thus to facilitate the stretching of the welt around the sharply curved toe portion of the shoe.

- The work support 20 comprises a bar carrying a
50 roll 32 mounted upon a vertical stud 34 on the bar, the upper portion of the roll being shaped to enter the welt crease of the shoe and the upper surface 36 of the roll being arranged for supporting the welt. Preferably, the surface 36 is beveled downwardly at an angle of about 5° to

the horizontal so that the welt will be supported principally upon the upper surface of the roll away from the edge portion adjacent to the welt crease, thus to relieve the pressure of the feed wheel upon the stitches so that the threads will not be pulled.

The work support is positioned between two vertically extending guides 38 (Figs. 1 and 5) carried by the frame and has a depending boss 40 (Fig. 7) slidably mounted heightwise of the frame in a sleeve 42, the boss terminating in a depending rod 44. Upon the lower end of the rod is located a bushing 46 screw-threaded into the sleeve, and there is a spring 48 between the upper end of the bushing and the boss 40 which normally operates to force the work support upwardly toward the feed wheel 24. The pressure of the spring is adjusted by rotating the bushing in the sleeve. Upward movement of the work support is limited by a nut 50 screw-threaded on the lower end of the rod 44 and engaging the lower end of the bushing 46. Vertical adjustment of the work support heightwise of the feed wheel is readily accomplished by rotating the nut which provides for adjustment of the spacing of the work support relatively to the feed wheel for welts of different thicknesses, for example, from $\frac{3}{16}$ to $\frac{1}{4}$ of an inch.

The feed wheel 24 is substantially cylindrical in shape and is provided with flutes 52 (Fig. 1) extending axially of the roll for gripping the welt to feed it substantially at right angles to the axis of the roll. It is found that the flutes extending in this manner facilitate the feed of the welt without preventing its movement outwardly of the shoe in stretching, with the result that there is little or no tendency for the feed wheel to crimp the welt during the feeding movement.

The hammers 26, of which preferably there are four as shown in Figs. 1 and 5, are mounted radially in a spider 54 in grooves 56, being locked in position in the spider by bolts 58. Each of the hammers is provided with a curved work engaging portion 60 which is relieved, as indicated at 62, in advance of the direction of rotation of the hammers, which is clockwise in Fig. 1. A guard 61 (Figs. 3 and 7) in the form of a circular plate is secured to the outer face of the spider by screws 63. Preferably the guard is formed of transparent plastic material to permit view of the work between the adjacent hammers.

The feed wheel 24 and the hammers 26 are driven by means of an electric motor 64 (Figs. 1, 2 and 5) mounted upon the upper portion of the frame 22. The feed wheel is driven from the motor through a pulley 66, a belt 68, reducing gear 70 (Fig. 2), and a belt 72 passing over a pulley 74 which drives a gear 76 in mesh with a second gear 78 carried by the shaft 80 to which the feed wheel is connected. The spider 54 carrying the hammers is mounted on a shaft 81 arranged to be driven by a pulley 82 on the shaft through a belt 84 from a pulley 86 on the motor shaft. Preferably, the hammers are rotated at about 2200 revolutions per minute and the feed wheel is driven at about 96 revolutions per minute, the relative sizes of the parts being such that the speed of the hammers across the face of the work is greater than the speed of feed of the work across the work support. In this way several blows of the hammers are delivered along each successive portion of the inseam materials as the shoe is advanced across the face of the work support.

The slashing knife 28 is mounted in a bracket 88 (Figs. 1, 5 and 6) carried at the lower end of

a knife arm 90 which is pivoted at 92 upon a U-shaped bracket 94 secured by bolts 96 to the work support 20. The knife is arranged for movement from inoperative position to a position closely adjacent to the surface 36 of the work support and below the feed wheel. Since the work support and support for the knife arm are secured together, movement of the work support in accommodating itself to different thicknesses of welt will not change the relative position of the knife in its slashing movement and the surface 36 of the roll 32, with the result that the knife will always penetrate the work to the same distance from the grain side of the welt positioned upon the surface of the roll. The knife arm is normally held in inoperative position against a stop 98 on the bracket 94 by the force exerted by a spring 100 extending from a portion of the frame to a pin 102 on the knife arm.

The knife arm 90 carries a stud 104 which extends through an elongated opening 106 in a knife actuating arm 108 mounted upon an eccentric 110 on a shaft 112. Movement of the knife arm relatively to the arm 108 is accomplished by means of a toggle comprising a link 114 pivoted upon one end of the arm 108 and a link 116 pivoted upon the stud 104, the remaining ends of the links being pivoted at 117 (Figs. 5 and 6) to a movable control member 118. The upper end of the control member 118 has an elongated slot 120 which is positioned over a pin 122 on an arm 124 of a bell-crank lever 126 mounted in brackets 128 on the frame of the machine. The other arm 130 of the bell-crank lever is pivotally connected at 132 to the upper end of a treadle rod 134, the lower end of the rod being secured to an arm 136 of a foot treadle 138 pivoted at 140 on the frame. A spring 142 connected between a bracket 144 on the frame and a pin 146 on the treadle rod 134 normally tends to force the rod upwardly in a direction to turn the bell-crank 126 in a clockwise direction (Fig. 5) with the result that the arm 128 and control member 118 are urged upwardly to hold the toggle links 114, 116 in broken position, as shown in Fig. 5, with the knife arm 90 in position against the stop 98. Upward movement of the arm 124 is limited by a stop 148 mounted upon a stationary bracket 150. Depression of the treadle results in downward movement of the control member 118 and straightening of the toggle links 114, 116, and holding the stud 104 in position at one end of the slot 106 as shown in Fig. 6, with the result that the knife arm 90 is operatively connected for oscillatory movement with the arm 108. The lowermost position of the arm 124 is determined by a stop 152 also carried by the bracket 150. Both the upper and lower stops are manually adjustable and arranged to be secured in fixed positions by means of screw bolts 154 operating in elongated slots 156 in the stops.

The arm 108 for actuating the knife arm 90 is oscillated by means of the eccentric 110 on the shaft 112, the shaft being rotated by means of a pulley 158 driven by a belt 160 on a pulley 162 on the motor shaft 164.

In the operation of the machine, a shoe such as the shoe 10 (Fig. 3) is presented to the work support 20 with the roll 32 extending into the welt crease of the shoe and the welt 14 resting grain side down upon the upper face of the roll 32, the work support 20 being yieldable downward against the force of the spring 48 to permit insertion of the welt between the roll and the feed wheel 24. As the feed wheel rotates, the shoe

is advanced past the work support, the feed wheel serving to stretch out the welt to flatten it and the hammers 26 operating to beat down the in-seam materials. When the shoe has advanced so that the toe portion thereof is located upon the work support, the operator depresses the treadle 138 which effects a straightening of the toggle 114, 116 holding the knife arm 90 temporarily at the left end of the slot 106 of the arm 108, Fig. 7, with the result that the arm causes movements of the knife about the pivot 92 to slash the welt as indicated by reference characters 30 in Fig. 4. Preferably, the timing of rotation of the shaft 112 relatively to the feed wheel speed is such that the knife will effect three slashes per inch of feed, provided, of course, the treadle 138 is held depressed. When the treadle is released, the toggle is broken by raising the inner ends of the links 114, 116 and the spring 100 returns the knife arm 90 into inoperative position against the stop 98.

Having described my invention, what I claim as new and desire to secure by Letters Patent of the United States is:

1. A machine for operating on shoes comprising a feed wheel mounted for rotation about a fixed axis, a support for the welt of a shoe to be operated upon, means for yieldably mounting the work support for movement toward and away from the feed wheel, a welt slashing knife, means for pivotally mounting the knife upon the work support, and manually controlled means for effecting operation of the knife upon the welt.

2. A machine for operating upon shoes comprising a support for the welt of a shoe to be operated upon, a tool for operating upon the welt of the shoe, means for yieldably mounting the support for movement relatively to the tool, a slashing knife pivotally mounted upon the support, a power operated knife actuating member, and manually controlled means for operatively connecting the knife to the actuating member to effect an operation of the knife upon the welt.

3. A machine for operating upon shoes comprising a support for the welt of a shoe to be operated upon, means for advancing the welt across the support, means for yieldably mounting the support for movement toward and away from the feeding means, a welt slashing knife, means for pivotally mounting the knife upon the support, and manually controlled means for effecting operation of the knife upon the welt.

4. A machine for operating upon shoes comprising a support for the welt of a shoe to be operated upon, a feed wheel for advancing the welt across the support, means for yieldably mounting the support for movement toward and away from the feed wheel, a bracket movable with the support, a welt slashing knife mounted upon the bracket, and manually controlled means for effecting operation of the knife upon the welt.

5. A machine for operating upon shoes comprising a work support, a rotatable work engaging roll carried by the support, a feed wheel spaced from the roll, means for yieldably mounting the

support for movement relatively to the feed wheel, a slashing knife pivotally mounted upon the support, a power oscillated knife actuating member, and manually controlled means for operatively connecting the knife to the actuating member to effect operation of the knife.

6. A machine for operating upon shoes comprising a feed wheel mounted for rotation about a fixed axis, a support for the welt of a shoe to be operated upon, means yieldably mounting the work support for movement toward and away from the feed wheel, a bracket carried by the work support, an arm pivotally mounted upon the bracket, a slashing knife carried by the arm, a knife actuating member, means for oscillating the actuating member, a toggle comprising two links connected respectively to the knife arm and the actuating member, and manually operable means for straightening the toggle thereby operatively to connect the knife arm to the actuating member.

7. A machine for operating upon shoes comprising a feed wheel mounted for rotation about a fixed axis, a support for the welt of a shoe to be operated upon, means mounting the support for movement toward and away from the feed wheel, a bracket carried by the support, an arm pivotally mounted upon the bracket, a slashing knife carried by the arm, a stop upon the bracket, a spring normally operative to force the arm toward the stop, a knife actuating member, power operated means for oscillating the actuating member, a toggle comprising two links connected respectively to the knife arm and the actuating member, and manually operable means for straightening the toggle whereby the knife arm is operatively connected to the actuating member.

8. A machine for operating upon shoes comprising a support for the welt of a shoe to be operated upon, means for advancing the welt across the support, means for yieldably mounting the support for movement toward and away from the feeding means, a welt slashing knife, means for pivotally mounting the knife upon the support, a stop on the support, a spring normally operative to force the knife into inoperative position determined by the stop, and manually controlled means for effecting operation of the knife upon the welt.

50 9. A machine for operating upon shoes comprising a support for the welt of a shoe to be operated upon, means for advancing the welt across the support, means for yieldably mounting the support for movement toward and away from the feeding means, a welt slashing knife, means for pivotally mounting the knife upon the support, a stop on the support, a spring normally operative to force the knife into inoperative position determined by the stop, a power oscillated actuating member, toggle links connecting the knife and the actuating member, and manually controlled means for straightening the toggle to cause the actuating member to effect an operation of the knife.

CORWIN W. BAKER.
